UNITED STATES PATENT OFFICE.

OSCAR F. HABERLAND, OF PHILADELPHIA, PENNSYLVANIA, ASSIGNOR TO HIMSELF
AND HARRY J. DIXON, OF PHILADELPHIA, PENNSYLVANIA.

SELF-PROPELLED EXPLOSIVE TOY.

1,247,108.

Specification of Letters Patent. Patented Nov. 20, 1917.

Application filed June 25, 1917. Serial No. 176,659.

To all whom it may concern:

Be it known that I, OSCAR F. HABERLAND, a citizen of the United States, residing at 6027 Market street, Philadelphia, in the 5 county of Philadelphia and State of Pennsylvania, have invented a certain new and useful Self-Propelled Explosive Toy, of which the following is a specification.

The purpose of my invention is to make 10 the "explosion" of a toy automatic and the toy movable.

A further purpose is to imitate "mine" destruction in such a toy.

A further purpose is to provide such a toy 15 with motor-driving mechanism for land or water use and a ram for causing the explosion when the ram engages an obstacle.

A further purpose is to provide driving- 20 mechanism for conveying an explosive toy from place to place with tripping mechanism for releasing the spring to scatter the parts of the vessel at a predetermined point in the progress of the toy.

A further purpose is to apply flexible op- 25 erating means controlled at a distance from the toy for releasing the detent of the spring of a movable explosive toy to control its time and place of explosion absolutely.

A further purpose is to apply any pair 30 or all of these means of releasing the detent of an explosive toy to the same device.

Further purposes will appear in the specification and in the claims thereof.

I have preferred to illustrate my invention by but one general form thereof, selecting a form which is practical, efficient, inexpensive and which, at the same time, well illustrates the principles of my invention.

40 Figure 1 is a side elevation of a preferred form of my invention.

Figs. 2 and 4 are vertical, longitudinal sections of structures similar to Fig. 1, differing in detail.

45 Fig. 3 is a top plan view of a structure of the general type seen in Fig. 1 but with the deck removed.

Fig. 5 is a perspective view of a ram and catch shown in Fig. 4.

50 My invention is directed toward a type of toy made of separable parts resting over or in any suitable relation to a spring, retained in position by a detent so that when the detent is operated the spring is released and

the separable parts of the toy are scattered 55 as if by an explosion.

As the invention finds its best illustration in a vessel which is apparently blown up by a mine, I shall describe it in these terms, though I recognize that other forms of toy 60 ("tanks," for example) may also be "mined" acceptably to the toy-purchasing public.

The vessel 1 is shown as mounted upon pairs of wheels 2 and 3 of which the pair 2 preferably drive and the pair 3 may be 65 steering wheels. It is also provided with a screw propeller 4 upon a shaft 5, by which propeller the vessel may be operated in water.

Any suitable spring motor will turn the 70 wheels or propeller. I have shown a spring 6 and conventional clock-work mechanism 7 such as is used in driving smaller toys with the difference, however, that whereas most of these toys have but one means of propulsion, the clock-work train in the present case 75 may drive either or both means shown.

The various upper parts of the vessel are 80 separable from the body and capable of being scattered by suitably arranged spring operated mechanism. I will describe one 85 form of this construction, recognizing, however, that the arrangement by which the parts are supported, their lines of separation and the spring mechanism and connections by which they are scattered, may be widely varied.

In my illustration I cover the vessel by a light main deck 8 upon which all of the other parts are separably mounted, and 90 throw the deck upwardly by spring means to scatter the parts. Upon the main deck I show loose auxiliary decks 9 and 10, funnels 11, military masts 12 and turrets 13. The auxiliary decks, funnels, masts and turrets are provided with pins 14 resting in corresponding recesses 15 in the parts next beneath them.

95 The operating mechanism preferred by me to throw the parts upwardly comprises 100 a spiral spring 16 and extending loop 17 of "mouse trap" form secured to a bar 18 and retained in set position by a latch or detent 19.

105 My invention is directed primarily to the application of the "exploding" toy idea to a moving toy in which the spring is or may be released as a result of the toy's movement,

This character of spring release is treated herein as "automatic." It will be obvious that the "mine explosion" could be set off by the motor whether the car be driven or not.

5 I provide three different means for automatic release of the detent; by a front contact, likened to a ram; by a trip connected with the propelling mechanism; and by a flexible connection, which may be tied or held to set the distance at which explosion

10 shall take place at any time desired.

The ram 20 is suitably guided and supported to project beyond the front of the vessel when the latch or detent is set and to engage or move the detent when the projection is forced rearwardly with respect to the car. The ram is separate from the detent in Fig. 2 and integral with it in Figs. 4 and 5.

20 In Fig. 2 the ram is shown as engaging a pivoted detent between the point 21 at which it is pivoted in bracket 22 and the catch 23. Collar 24 prevents complete withdrawal of the ram.

25 The same detent may also be tripped by a flexible connection 25 secured at 26 and passing out through the vessel at 27.

Upon one of the shafts of the spring motor 7 I place a sprocket 28 which coöperates with a sprocket 29 mounted in brackets 30 to support and drive a chain 31. A lug 32, at any suitable point upon the chain projects therefrom to engage the detent 19 and release it at a predetermined point in the vessel's travel. By merely removing and resetting the chain this point may be adjusted with exactness by the user of the toy.

The selection of the motor shaft upon which sprocket 28 is placed depends both upon the speed and direction of sprocket travel preferred.

In Figs. 4 and 5 the detent 19' is directly connected with the ram and has a horizontal movement instead of a swinging movement.

45 This direct connection possesses one advantage, in that spring resetting of the ram, as by compression spring 33 between collar 24 and bracket 34, sets the detent, giving a convenient means of setting the detent from the outside to hold the spring. As the width of the toy does not give much room for the hand otherwise used to set the latch or detent in addition to the hand required to set the spring some automatic or outside setting 55 of the detent is desirable.

In Fig. 4 a second form of motor-operated tripping mechanism is shown. The ram is extended far enough to bring a hook 35 upon its end within the path of travel of a lug or pin 36 in a wheel 37 which may be one of the original gears of the motor or an extra gear, as may be convenient.

In both of the motor-actuated tripping mechanisms, shown in Figs. 2 and 4, the engagement of the lug upon the chain or upon

the gear with the detent or extension of the ram may be used to stop the travel of the vessel. To make this more quickly effective in Fig. 2, I limit the pivotal movement of the detent by a stop 38.

70 By disconnecting the spring motor from the driving mechanism the "mine" may be operated automatically upon a stationary boat. This can easily be accomplished by moving one of the gears, as 39 (Fig. 3) laterally to disconnect it from its mating gear. If this be intended there is greater need for selection of a motor provided with an escapement or other governor than where the propulsion of the car itself 80 retards the motor.

It will be obvious that the character of the spring and detent, the connections between the detent and the release mechanisms, the mechanisms for stopping travel 85 of the vessel, and the detail of the releasing mechanisms themselves may be varied greatly without departing from the spirit and scope of my invention.

90 I claim—

1. A toy having spring-thrown separable parts, comprising a body portion, a removable top portion therefor, loose parts rested on the top portion, a spring adapted, when released, to scatter the parts, a detent 95 engaging the spring to hold it in set position, spring driving mechanism for the toy and connections between the driving mechanism and the detent, whereby the detent is released at a predetermined point in the 100 unwinding of the spring driving mechanism.

2. A toy having spring-thrown separable parts, comprising a body portion, loose parts resting upon the body portion, a spring 105 engaging the loose parts when it is released to scatter them, a detent for holding the spring in set position, spring driving mechanism for the toy, and connections between the spring driving mechanism and the detent, whereby the detent is released by unwinding operation of the driving mechanism.

3. A motor driven toy having separable parts adapted to be scattered by spring action, comprising a body portion, a driving motor therefor, separable parts on the body portion, a spring by which the separable parts are thrown upon release of the spring, a detent for holding the spring in set position, and release mechanism for the detent automatically operated by reason of unwind- 115 operation of the motor.

4. A toy having separable parts adapted to be blown up by spring operation which 120 consists of a body portion, means for driving the body portion bodily, loose parts above the body portion, a spring for scattering the separable parts, a detent for holding the spring in set position and automatic 125

spring-actuated means for releasing the spring from the detent at a predetermined point in the travel of the toy.

5. A toy adapted to be blown up by spring operation, comprising a body portion, a spring motor therein, loose parts resting upon the body portion, a spring scattering the loose parts when released, a detent retaining the spring in set position, and a 10 release for the detent operatively connected with the motor and effective with unwind-movement of the motor.

6. A toy adapted to be blown up by spring operation and comprising a body portion, 15 driving means therefor, loose parts resting upon the body portion, a spring device for scattering the loose parts when the spring is released, a detent retaining the spring in set position and a driving-mechanism-operated release for the detent.

7. A toy adapted to be blown up by spring operation and comprising a body portion, driving means therefor, loose parts resting upon the body portion, a spring device for 25 scattering the loose parts when the spring is released, a detent retaining the spring in set position, a chain operatively connected with the driving mechanism, and means on the chain for releasing the detent at a predetermined point in the unwind-movement of the driving mechanism.

8. A separable toy, spring means for scattering the parts, a propelling device for the toy, an impact-operated release for the 30 spring located at the front end of the toy

and connections between the propelling device and the release to operate it from said propelling device.

9. A toy having loose parts adapted to be blown up by spring action and comprising a body portion, loose parts rested thereon, a spring adapted to scatter the parts, a detent retaining the spring in set position and a plurality of operating devices for releasing said detent, one of them being motor-actuated. 40

10. A toy having loose parts adapted to be blown up by spring action and comprising a body portion, loose parts rested thereon, a spring adapted to scatter the parts, a detent retaining the spring in set position, a motor driving the toy bodily, and a plurality of operating devices for releasing said detent, one of them being impact-operated and the other automatic. 45

11. A toy having loose parts adapted to be blown up by spring action and comprising a body portion, loose parts rested thereon, a spring adapted to scatter the parts, a detent retaining the spring in set position, a motor driving the toy bodily and an operating mechanism for releasing said detent by reason of continued movement of the toy. 50

12. A blow-up toy having detachable parts, motor propelling mechanism therefor and means operated by the propelling mechanism for putting the blow-up feature in operation. 55

OSCAR F. HABERLAND.
